OF NEW JERSEY.

DRILLING-MACHINE.

1,135,475.

Specification of Letters Patent. Patented Apr. 13, 1915.

Application filed March 31, 1913. Serial No. 757,819.

To all whom it may concern:

Be it known that we, HENRY WANAMAKER and JOSEPH McALLISTER, of Albany, Albany county, New York, have invented certain new and useful Improvements in Drilling-Machines, of which the following is a specification.

The object of our invention is to provide a simple, efficient and reliable drilling machine intended more particularly for the purpose of drilling holes or for counter sinking such holes in a sheet or plate at an angle with the axis of the prime mover without recourse to a so-called "old man" or any fixtures other than the piece undergoing the operation and the prime mover.

A further object of our invention is to provide such a drilling machine with means for automatically restricting the depth of the hole being drilled to the required limit and to feed or force the cutting tool into the piece as the operation progresses.

Owing to the great force necessary to hold a drilling machine in place by means of the ordinary fixture during its operation, there is a tendency for such machine to work loose from its connection with the piece on which work is being done, which frequently occurs and often results in physical injury to the operators. Also the prior method in which such fixture is employed requires the loosening and tightening of the fixture every time a new hole is to be drilled thereby adding much to the labor and greatly increasing the possibility of accident. My drilling machine overcomes all of these objections inasmuch as it entirely dispenses with the use of such fixture by providing a fixture which is practically a part of the prime mover and causes the drill to be presented and to be fed by motive fluid which in the present instance is the same motive fluid which actuates the prime mover.

In the drawings Figure 1 is a perspective of our drilling machine shown in working position upon a boiler head; Fig. 2 an elevation thereof with the lower portion in section, the parts being the same as shown in Fig. 1 with the exception of the throttle valve; and Fig. 3 a top plan view of the yoke or frame which cooperates with the prime mover and which carries the drilling tool.

While our invention may partake of different embodiments without departing from the scope of the claims, we prefer the embodiment as herein shown which will now be described.

Referring to the particular construction herein described, the prime mover indicated generally by the reference figure 1 may be of any suitable construction and operated by suitable motive fluid such as compressed air but in the present instance such prime mover or engine is shown as of the corner drill type with its rotatable spindle 2 at one extreme end thereof. The motive fluid enters through the pipe 3 from the flexible hose supply pipe 4, the motive fluid being throttled or governed by a suitable hand operated valve 5. In Fig. 1 this valve is shown as an ordinary 2-way valve operated by a handle 6 and in Fig. 2 such valve is of the type exemplified in Boyer Patent No. 663,355 dated September 19, 1899, the valve proper (not shown) being operated by means of the sleeve 7. Extending in the line of the axis of the body of the prime mover and connected therewith as hereinafter described is a frame or yoke 8, preferably of the shape or formation clearly illustrated in Figs. 1 and 2. This frame is extended at one end to form an arm 8^a which contains a bearing for a short shaft 9 entering the hollow spindle 2 which as usual may have the ordinary Morse taper. In this manner the shaft 9 is driven by the prime mover and such shaft also forms one of the connections between the prime mover and the frame or yoke. At its lower or outer end the shaft 9 is provided with a bevel gear 10 which meshes with a corresponding bevel gear 11 secured to the outer end of the short shaft 12. This latter shaft has its bearings in an arm 8^b of the yoke or frame and to its outer end is secured in suitable way as by means of the tapered pin 13 the proper cutting tool 14.

The other main arm 8^c of the yoke or frame is provided with a piston chamber or cylinder 15 which is open at its end adjacent the cutter but of restricted diameter thereat in order to receive the stem 16^a of a piston 16 movable in such cylinder. The outer end of this piston stem or plunger is hollow as shown at 16^b for a purpose here-

2
 inaftter made apparent. The outer or rear end of the cylinder is connected in suitable manner with the supply of the motive fluid as fed to the prime mover and in 5 the present instance this connection consists of a T 17 in the pipe 3 and detachable pipe connections shown in general by the reference number 18, such latter connections entering the piston chamber through 10 the port 19, whereby when the prime mover is operating the motive fluid is at the same time admitted against the rear pressure area of the piston 16 to force such piston and its plunger outwardly, that is to the left in 15 Fig. 2 against the tension of a spring 20 arranged in the cylinder and around the plunger and intended to restore the piston to normal position when the motive fluid is cut off.

20 The purpose of the piston and its plunger is to force or feed the tool to the work indicated by the reference letter A to the drill as the drilling operation proceeds and it is evident that this action is automatic because 25 it occurs at the time of and as incident to the starting of the prime mover in its operation by the admission of motive fluid thereto, the admission of such motive fluid to the piston chamber 15 being simultaneous which represents the preferred construction and arrangement.

We prefer to provide our drilling machine with means for automatically restricting the depth of the hole being drilled to the required limit and to this end the piston is provided with a rod 21 formed separate or integral therewith and extending rearwardly through the screw cap 22 closing the rear end of the piston chamber and 40 through the packing 23 in such cap, such packing being provided with the usual gland nut 24. The outer end of the rod 21 is screw-threaded and provided with an adjustable nut 25 and a lock nut 26. It will 45 be evident that the nut 25 by coming into contact with the nut 24 will determine the extent of outward movement of the piston and its plunger and that by adjusting this nut 25 the extent of outward movement may 50 be determined. In this manner the feed of the work to the tool may be stopped when such tool reaches the required depth of hole with the result that such depth may be obtained to a nicety. The outer end of the 55 plunger is provided with the opening or cavity described in order to admit the cutting tool in the drilling of holes in the plate or sheet.

By the use of our invention the ordinary fixtures which are unreliable as hereinbefore made manifest are entirely dispensed with and the yoke or frame which is connected to the prime mover is so made as to take the place of such a fixture and at the same time 65 it embodies the automatic features hereinbe-

fore described. By such construction and arrangement we are enabled to drill holes or to countersink them (according to the particular cutting tool employed) with great facility and economy as well as accuracy without any danger of injury to the operator, besides which a degree of accuracy and uniformity in the work is obtained which is not obtainable in drilling machines previously used for the same purposes. 75

We claim:

1. In combination with a prime mover having a rotatable driving member, a frame arranged in a line parallel to the axis of the prime mover and at an angle to said driving member, said frame having a bearing for said driving member, a cutting tool in such frame, and driving connections between said member and tool. 80

2. In combination with a prime mover 85 having a rotatable driving member, a frame arranged in a line parallel to the axis of the prime mover and at an angle to said driving member, said frame having a bearing for said driving member, a cutting tool in such frame, driving connections between said member and tool, and fluid pressure operated means for feeding the tool to the work. 90

3. In combination with a prime mover 95 having a rotatable driving member, a frame arranged in a line parallel to the axis of the prime mover and at an angle to said driving member, said frame having a bearing for said driving member, a cutting tool in such frame, driving connections between said member and tool, said prime mover being actuated by fluid pressure, and means operated by the same fluid pressure as supplied to the prime mover for feeding the 105 tool to the work. 100

4. In combination with a prime mover having a rotatable driving member, a frame arranged in a line parallel to the axis of the prime mover and at an angle to said driving member, a cutting tool in such frame, driving connections between said member and tool, and fluid pressure operated means mounted in said frame for feeding the 110 tool to the work. 115

5. In combination with a prime mover having a rotatable driving member, a frame arranged in a line parallel to the axis of the prime mover and at an angle to said driving member, a cutting tool in such frame, driving connections between said member and tool, and fluid pressure operated means mounted in said frame for feeding the work to the tool comprising a cylinder in said frame, a piston therein having a plunger 120 adapted to press against the work to bring the tool against the work, and means for supplying fluid under pressure to the cylinder. 125

6. The combination with a prime mover 130

having a rotatable driving member, a frame arranged in a line parallel to the axis of the prime mover and at an angle to said driving member, a cutting tool in such frame, driving connections between said member and tool, and fluid pressure operated means mounted in said frame for feeding the work to the tool comprising a cylinder in said frame, a piston therein having a plunger 10 adapted to press against the work to bring the tool against the work, and means for supplying fluid under pressure to the cylinder, said plunger being hollow at its outer end to accommodate the tool.

15 7. In combination with a prime mover having a rotatable driving spindle, a frame, a shaft mounted to rotate therein and adapted to be operatively connected with the spindle, a second shaft mounted to rotate in the 20 frame and operatively connected with the first shaft, a cutting tool carried by such second shaft, a cylinder in said frame, a piston therein having a plunger adapted to press against the work to bring the tool 25 against the work, and means for supplying fluid under pressure to the cylinder.

8. In combination with a prime mover having a rotatable driving member, a frame arranged in a line parallel to the axis of the 30 prime mover and at an angle to said driving member, a cutting tool in such frame, driving connections between said member and tool, and fluid pressure operated means mounted in said frame for feeding the work to the tool comprising a cylinder in said frame, a piston therein having a plunger adapted to press against the work to bring the tool 35 against the work, said prime mover being actuated by fluid under pressure, and 40 means for supplying to the cylinder the same fluid under pressure as supplied to the prime mover.

9. In combination with a prime mover having a rotatable driving member, a frame 45 arranged in a line parallel to the axis of the prime mover and at an angle to said driving member, a cutting tool in such frame, driving connections between said member and tool, and fluid pressure operated means 50 mounted in said frame for feeding the work to the tool comprising a cylinder in said frame, a piston therein having a plunger adapted to press against the work to bring the tool 55 against the work, said prime mover having a fluid pressure supply pipe, and a connection between such pipe and the cylinder for conveying motive fluid to the cylinder.

der and also physically connecting the prime mover and frame together.

10. In combination with a prime mover 60 having a rotatable driving member, a frame arranged in a line parallel to the axis of the prime mover and at an angle to said driving member, a cutting tool in such frame, driving connections between said member and 65 tool, fluid pressure actuated mechanism which is movable to feed the tool to the work, and means for limiting the degree of movement of such mechanism.

11. In combination with a prime mover 70 having a rotatable driving member, a frame arranged in a line parallel to the axis of the prime mover and at an angle to said driving member, a cutting tool in such frame, driving connections between said member and 75 tool, fluid pressure actuated mechanism which is movable to feed the work to the tool, and adjustable means for predetermining the degree of movement of such mechanism. 80

12. In combination with a prime mover having a rotatable driving spindle, a frame, a shaft mounted to rotate therein and adapted to be operatively connected with the spindle, a second shaft mounted to rotate in 85 the frame and operatively connected with the first shaft, a cutting tool carried by such second shaft, a cylinder in said frame, a piston therein having a plunger adapted to press against the work to bring the tool 90 against the work, said piston having a rod passing through one end of the cylinder, and an adjustable member thereon for limiting the outward movement of the piston.

13. In combination with a prime mover 95 having a rotatable driving spindle, a frame, a shaft mounted to rotate therein and adapted to be operatively connected with the spindle, a second shaft mounted to rotate in the frame and operatively connected with the 100 first shaft, a cutting tool carried by such second shaft, a cylinder in said frame, a piston therein having a plunger adapted to press against the work to bring the tool against the work, said piston having a rod 105 passing through one end of the cylinder, and an adjustable nut therein adapted to contact the end of the cylinder to limit the outward movement of the piston.
